UNITED STATES PATENT OFFICE

161,627

FLAT WALL WHATNOT

Robert L. Haworth, Indianola, Iowa

Application October 12, 1950, Serial No. 12,533

Term of patent 14 years

(Cl. D33—3)

To all whom it may concern:

Be it known that I, Robert L. Haworth, a citizen of the United States of America, residing at Indianola, county of Warren, and State of Iowa, have invented a new, original, and ornamental Design for a Flat Wall What-Not, of which the following is a specification, reference being had to the accompanying drawing, forming a part thereof wherein:

Figure 1 is a perspective view of a flat wall what-not, showing my new design;

Figure 2 is a view in front elevation of the flat wall what-not, and

Figure 3 is a view in side elevation of the flat wall what-not.

I claim:

The ornamental design for a flat wall what-not, as shown.

ROBERT L. HAWORTH.
